CLAIM

The ornamental design for a toolbox creeper as shown.

DESCRIPTION

FIG. 1 is a perspective view of a toolbox creeper of the present design;

FIG. 2 is a front view thereof;

FIG. 3 is a rear view thereof;

FIG. 4 is a left-side view thereof;

FIG. 5 is a right-side view thereof;

FIG. 6 is a top view thereof.

FIG. 7 is a bottom view thereof;

FIG. 8 is another perspective view showing the toolbox creeper in an alternate configuration with the drawers open.

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the figures depict portions of the toolbox creeper that form no part of the claimed design.

1 Claim, 14 Drawing Sheets
